UNITED STATES PATENT OFFICE.

DENNIS J. KANE, OF BOSTON, MASSACHUSETTS.

DESIGN FOR A BED-BOTTOM.

SPECIFICATION forming part of Design No. 27,534, dated August 17, 1897.

Application filed April 23, 1897. Serial No. 633,537. Term of patent 7 years.

To all whom it may concern:

Be it known that I, DENNIS J. KANE, of Boston, in the county of Suffolk and State of Massachusetts, have invented a certain new and useful Design for Bed-Bottoms, of which 5 the following is a description.

The drawing shows a perspective view of a bed-bottom embodying my design.

The leading feature of my design consists 10 of a bed-bottom whose sides have a continuous zigzag or wave-like outline and whose ends have separate V-shaped sections, the outermost portions of said sides and ends having angular extensions projecting above 15 the plane of the bottom.

The bed-bottom is formed of zigzag strips A, being joined together at regular or nearly regular distances apart alternately with the adjacent strips on either side, (these points 20 of union being lettered a and b in the drawings,) thus producing a series of approximately diamond-shaped sections. These series extend obliquely to the sides of the bed

at the outwardly-projecting parts c of the zigzag sides, so forming the outwardly-projecting ears or hooks. The strips A converge in pairs at the ends d, and also terminate in outwardly-projecting ears. 25

My design, as above described, dispenses entirely with the usual rectangular straight-sided frame, and its novel configuration results in obvious advantages. 30

Having described my invention, what I claim as new, and desire to secure by Letters Patent, is—

The design for a bed-bottom, as herein shown and described. 35

In testimony whereof I have signed my name to this specification, in the presence of two subscribing witnesses, this 13th day of April, A. D. 1897. 40

DENNIS J. KANE.
